LIGHTING FIXTURE

Leroy C. Doane, Meriden, Conn., assignor to The
Sight Light Corporation, Essex, Conn., a cor-
poration of Connecticut

Application December 21, 1938, Serial No. 246,944

9 Claims. (Cl. 248—276)

The present invention relates to lighting fixtures, and is more particularly directed toward lighting fixtures adapted for mounting on a vertical support, such as a wall.

The present invention contemplates lighting fixtures which can be moved up and down so as to adjust the mounting height, and in which an arm carrying the light controlling elements is pivoted so that it can be swung about in a horizontal arc.

The present invention also contemplates fixtures of this type in which the arm can also be swung in a vertical plane so as to be brought from the normal horizontal position to a pendent position, and according to the present invention locking devices are provided whereby the arm can be locked so as to swing in the horizontal plane only, or so as to swing only in the vertical plane.

The invention also contemplates that the light controlling elements carried on the end of the arm can be turned through 90° so as to be brought from the normal horizontal position for directing light downward into a vertical position where they occupy less space.

In a modified form of construction the light controlling elements are carried in such a way as to be removable from the supports so as to be held in the hand.

Other and further objects will appear as the description proceeds.

The accompanying drawings show, for purposes of illustrating the present invention, two of the many embodiments in which the invention may take form, it being understood that the drawings are illustrative of the invention rather than limiting the same.

In these drawings:

Figure 1 is a side elevational view of a lighting fixture, the dot and dot-and-dash line positions indicating certain of the movements possible;

Figure 2 is a top plan view of the lighting fixture dot and dot-and-dash line positions indicating other possible movements;

Figure 3 is a side elevational view illustrating the parts in a still different position;

Figure 4 is a vertical sectional view taken on the line 4—4 of Figure 2;

Figure 5 is a horizontal sectional view taken on the line 5—5 of Figure 4;

Figure 6 is a vertical sectional view taken on the line 6—6 of Figure 4;

Figure 7 is a sectional view taken on the line 4—4 of Figure 2 with the parts swung into an intermediate position;

Figure 8 is a vertical sectional view taken on the line 8—8 of Figure 3;

Figure 9 is a side elevational view of a modified form of construction;

Figure 10 is a vertical sectional view taken on the line 10—10 of Figure 11;

Figure 11 is a horizontal sectional view taken on the line 11—11 of Figure 10;

Figure 12 is a vertical sectional view taken on the line 12—12 of Figure 9; and

Figure 13 is a view showing the light controlling elements of the structure of Figure 9 detached.

The structure shown in Figures 1 to 8, inclusive, is designed more particularly for use on shipboard where it is necessary to economize in space and to have lighting equipment mounted so that it will not shift during movement of the ship.

A bulkhead or other suitable support is indicated at 20. A vertically extending guide member 21 is suitably secured to the bulkhead as, for example, by screws indicated at 22. This guide member 21 is of generally C-shaped cross section and may be made out of stamped or extruded metal. It has inwardly extending flanges 23 and 24 which are spaced to form a laterally opening slot 25.

A slider 26 is received in the guideway. This slider has laterally extending edges which extend into the side guides provided by the flanges 23 and 24 as more clearly shown in Figure 5. On the front side of the slider are spring members 29 and 30 which extend in behind the flanges 23 and 24 and bear on them to provide friction which resists movement of the slider. These two springs may be made of a single piece of material, if desired. The flanges 23 and 24 of the vertical guide member are notched as indicated at 31 and 32, so that ends 33 and 34 of the springs 29 and 30 may enter them and lock the slider against movement under desired conditions.

The slider 26 has an outwardly extending element 35 which passes through slot 25 and carries a pivot pin 36 placed substantially in the plane of the flanges 23 and 24. This pin pivotally supports a bell-crank shaped member 37. The upper arm 38 of this member has two laterally extending flanges 39 which are adapted to pass down behind the flanges 23 and 24 when the bell-crank 37 is in the position shown in Figures 1, 2, 4, 5 and 6, and when the bell-crank is in this position the slider can be moved up and down in the guide as indicated by the dotted line position of Figure 1 and the dot-and-dash line position of Figure 4. When in the position shown in full lines in

Figure 4, it is locked against sliding by the end 34 of the spring entering the notch 32. The lower arm 40 of the bell-crank member has laterally extending flange elements 41 and 42 which, when the slider is moved to the position indicated in dot-and-dash lines in Figure 7, can be passed through the notches 32 and extend behind the flanges 23 and 24, and when the bell-crank member is brought to this position, the slider can be moved up and down. It can be locked against downward movement when in the position shown in dot-and-dash lines of Figure 7 by the upper end 33 of the spring 29 entering the notch 31, as shown in Figure 8.

The slider is held against accidental removal by screws such as 43 placed at the top and bottom of the guide, and the ends of the bell-crank are suitably notched as indicated at 44 and 45, so that these parts will clear the screw heads.

The upper part 38 of the bell-crank member carries a forwardly extending bearing plate 46, and a lamp supporting arm 47 is pivotally secured in place by a bolt 48 with suitable friction washer 49. The arm 47 is tubular and receives another tubular element 50 which is provided with a spring 51 which supports a button 52 and extends through a 90° slot 53 in the outer tube. The spring 51 carries a pin 54 adapted to pass through one or the other of two holes 55, 55' in the outer tube 47. The wiring may pass through an eyelet 56 in the arm 47 and is connected to a switch 57 and lamp socket 57' to light a lamp 58. The lamp is received between upper and lower reflectors 59 and 60. The latter-mentioned parts form the subject matter of a separate application.

The device shown in Figures 1 to 8, inclusive, is particularly designed as a bunk light on shipboard, the guideway 21 being fastened to a bulkhead. With this construction it is possible for one to adjust the bell-crank member so that the lamp supporting arm 47 extends out horizontally and to lock it at a desired elevation, or to slide it down to some lower elevation. When the arm is in the horizontal position the luminair can be swung around the vertical axis, as indicated in Figure 2, and if it is desired to stow the luminair flat against the bulkhead at the higher elevation the head can be swung through 90° relative to the arm axis and then the arm swung back to bring the parts to the dot-and-dash line position of Figure 1. If, on the other, it is desired to swing the arm down close to the bulkhead and have it hang downwardly, the parts can be brought to the positions shown in Figures 3, 7 and 8, and locked against sliding movement.

The arrangement shown in Figures 9 to 13, inclusive, is designed more particularly for a hospital bed light, and utilizes certain of the features of Figures 1 to 8, inclusive. It has a vertically extending guide member 61 similar to the guide member 21. This guide member accommodates a slider 62 similar to the slider 26 and the slider is frictionally held in place by springs indicated at 63 and 64. The slider has an outwardly extending element 65 which supports a tubular arm 66 for swinging about a horizontal axis 67. This arm is preferably made of square tubing, as indicated in Figure 12, and slidably receives a square rod or tube 68. The rod or tube 68 carries the head or luminair similar to that above described. The rod 68 is slideable in the tube 63 and may be locked in any selected place therein by a spring pressed button 69 adapted to pass through a hole 70 in the tube wall. In this case the wiring is ex-

teriorly carried, as indicated at 71, and one can remove the rod 68 from the tube and carry the luminair as a hand lamp. It makes a very satisfactory inspection lamp for the doctor to use at the bedside. The arm can be swung about in a horizontal plane and be raised and lowered to suit the convenience of the patient and staff.

It is obvious that the invention may be embodied in many forms and constructions within the scope of the claims and I wish it to be understood that the particular forms shown are but a few of the many forms. Various modifications and changes being possible, I do not otherwise limit myself in any way with respect thereto.

What is claimed is:

1. In combination, a vertically extending member of C-shaped cross section providing two guideways on the opposite sides of a laterally opening slot, a slider having sides received in the guideways and an element extending outwardly through said slot and adapted to carry a lamp, means for supporting the slider in adjusted position comprising a leaf spring carried by the slider and bearing frictionally against the vertically extending member, the vertically extending member being notched to receive an end of the spring means and lock the slider in a predetermined position, the spring being depressible to release the slider, and a luminair secured to said slider carried element.

2. A lighting fixture comprising a vertically extending member of C-shaped cross section providing two guideways on the opposite sides of a laterally opening slot, a slider having sides received in the guideways and an element extending outwardly through said slot, spring means carried by the slider and bearing against the vertically extending member to frictionally engage the same and support the slider in adjusted position, a horizontally extending pivot carried by the outwardly extending element, a vertically swingable bell-crank carried on the pivot, cooperative elements carried by the ends of the bell-crank and by the vertically extending member to lock the bell-crank in either of two positions 90° apart, a pivot carried by the bell-crank shaped member in a position to swing in a vertical plane, an arm carried by the last-mentioned pivot, and a lamp carrying arm swingable in a horizontal plane when the bell-crank is in one position and in a vertical plane when the bell-crank is in the other position.

3. A lighting fixture such as claimed in claim 2, wherein the lamp is connected to the end of the arm to be turned through an angle of 90° relative to the arm axis.

4. A lighting fixture such as claimed in claim 2, wherein the bell-crank is releasable for swinging when the slider is in predetermined position, and is locked against such movement when the slider is shifted from such a position.

5. A lighting fixture comprising a vertically extending notched guide, a slider therein having friction means for holding the slider and supported parts at a selected elevation, a bell-crank pivoted to the slider and having projections at the ends, each projection being passable through a notch when the slider is at the corresponding elevation and having an element engageable with the guide when the slider is moved away from said elevation and acting to lock the bell crank in the corresponding position, an arm pivoted to the bell-crank to be swung through a horizontal plane when the bell-crank is in one position and in a vertical plane when it is in

the other position, and a lamp socket carried by the arm.

6. A lighting fixture as claimed in claim 5, wherein the friction means includes leaf springs carried by the slider and bearing on the guide.

7. A lighting fixture comprising a vertically extending member having inwardly facing flanges forming two guideways, a slider carried therein and extending out between the flanges, a bell-crank member pivoted to the slider and having at one end laterally extending fingers adapted to be swung over the ends of the flanges and to slide down behind them to prevent swinging of the bell-crank about its pivot, the flanges being notched and the other end of the bell-crank having laterally extending fingers adapted, when the slider is moved to release the first-named fingers from the flanges, to pass through the notches to pass behind the flanges so that the slider may be moved vertically to cause the second-mentioned fingers to lock the bell-crank against swinging about the pivot, and a lamp carrying arm carried by the bell-crank.

8. A lighting fixture as claimed in claim 7, having a slider carried spring whose end is adapted to enter the slot when the first set of fingers are behind the flanges to hold the slider against movement.

9. A lighting fixture comprising a vertically extending guide having vertically spaced notches, a slider therein having friction means for holding the slider and supported parts at a selected elevation, a bell-crank pivoted to the slider to swing about a horizontal axis and having projections at the ends, the projection on the upper end being passable through the upper notch when the slider is at one elevation, the projection on the lower end being passable through the lower notch when the slider is at another elevation, the projections having elements engageable with the guide when the slider is moved vertically from said elevation and acting to lock the bell-crank in the corresponding angular position, two slider carried releasable locking devices, one cooperable with the upper notch when the lower element is displaced from the lower notch, the other cooperable with the lower notch when the upper element is displaced from the upper notch whereby the bell-crank can be simultaneously locked against vertical movement while in said respective displaced positions, and an arm pivoted to the bell-crank to be swung through a horizontal plane when the bell crank is in one position and in a vertical plane when it is in the other position.
